UNITED STATES PATENT OFFICE.

ALBERT G. MITCHUM, OF DAVENPORT, WASHINGTON.

AUTO FOLDING BED.

1,199,481.

Specification of Letters Patent. Patented Sept. 26, 1916.

Application filed October 23, 1915. Serial No. 57,492.

To all whom it may concern:

Be it known that I, ALBERT G. MITCHUM, a citizen of the United States, residing at Davenport, in the county of Lincoln and 5 State of Washington, have invented certain new and useful Improvements in Auto Folding Beds, of which the following is a specification.

My invention relates to folding bed bottoms, and is specially adapted to support a temporary bed in an automobile, for the use 10 of campers or other parties who for any reason find it necessary or desirable to sleep in the automobile.

15 The object is to provide a device of this character which can be easily and quickly secured in operative position in an automobile, and which can as easily be removed and folded into a small, short, compact package when not in use, so that it can be conveniently carried in the machine, occupying 20 but little room.

Further specific objects will appear in the subjoined description.

25 The invention consists in certain novel combinations and arrangements of parts hereinafter described and claimed, reference being had to the accompanying drawings which form a part of this application, and 30 in which—

Figure 1 is a perspective view of my device in operative position in an automobile, the side curtains of the automobile being omitted for the sake of clearness. Fig. 2 35 is a plan view of the device, showing the slats arranged in operative position. Fig. 3 is a plan view of the device partly folded. Fig. 4 shows the device folded and rolled up. Fig. 5 shows the stiffening rod used at 40 the end of the device not provided with slats; and, Fig. 6 is a perspective of one of the metal angles used on the longitudinal slats. Fig. 7 is a broken perspective showing modified means for connecting the free 45 ends of the transverse slats 3 and 4 with the free ends of the parallel slats 2^a and 2^b. Fig. 8 is a broken plan view showing one of the transverse slats riding up laterally over the spring 21 and approaching parallelism 50 with the longitudinal slat 2^a. Fig. 9 is a vertical section of the construction shown in Fig. 7; and, Fig. 10 is a perspective on an enlarged scale showing the corner connections illustrated in Fig. 7 in operative relation to each other, with the slats removed.

Referring to the specific construction of

my invention, the numeral 1 indicates the main or body portion of the device, which portion is formed of a single piece of strong flexible material, usually a piece of fabric 60 of some kind, such as heavy canvas or duck. At one end, this body portion is provided with a series of longitudinally disposed slats 2, equidistant from each other. These slats are riveted or otherwise suitably secured to the main body portion of the device, and their length is preferably equal to the width of the bed-bottom.

At the ends of the series of longitudinal slats 2, are two slats 3 and 4 extending at 70 right angles to the slats 2 when the device is in operative position. These transverse slats 3 and 4 are pivoted to the device at diagonally opposite corners of the slatted portion thereof, by the pivots 5 and 6 respectively; while at their other ends they are adapted to be engaged and held in operative position by removable bolts 7 and 8, which are of course also at diagonally opposite corners of the device. The pivots 5 and 75 6 and the bolts 7 and 8, at the ends of the transverse slats 3 and 4, extend on through the ends of the outer ones 2^a and 2^b of the series of longitudinal slats 2. From this construction it will be seen that when the 80 bolt 7 is removed, the bar 3 can be swung on its pivot 5 and brought into parallelism with the longitudinal slat 2^a, as indicated by the arrows leading from 7 to 8, the two bars lying in flat engagement with each 85 other when in this position. In like manner, the transverse slat 4 can be brought into parallel flat engagement with the outer one 2^b of the series of longitudinal slats as indicated by the arrows leading from 8 to 7. 90 95

At the forward end of the main or body portion 1 of my device I provide the transverse loop 9 extending across said end, which loop is formed by turning the end of the fabric back upon itself a short distance 100 and then stitching the two lapping sections together. The loop thus formed is made large enough to receive a substantial rod 10 which is inserted therein to stiffen the forward end of the section 1 when the device 105 is in operative position on the automobile.

Just to the rear of the loop 9 I provide two openings 11 in the section 1 to receive the two buckle-straps 12; while at the rear end of the device, at its corners, the straps 110 13 are securely attached by riveting or otherwise. These straps at the four corners of

the device serve to engage suitable parts of the automobile at the front and rear ends thereof to hold the device securely in operative position when in use.

5 The small angles 14 are secured to certain intermediate ones of the longitudinal slats 2 near the ends of said slats to form abutments or stops for the transverse slats 3 and 4 between their ends, when they are brought 10 to their operative position.

The slats 3 and 4 are of the same length as the longitudinal slats 2.

When the device is in operative position 15 on the automobile, the rear end of the slatted section rests on the back of the rear seat, and the front end of the same rests on the back of the front seat, while the forward portion of the bed-bottom not provided with slats extends on from the back of the front seat 20 toward the forward end of the automobile. This latter part of the device, which supports the feet of the occupants of the bed is held suitably taut transversely by the slat 4 at the rear end of said portion and the rod 25 10 at the front end thereof.

In operating the device, when it is desired 30 to fold up the same, it is loosed from the automobile by means of the front and end buckle straps 12 and 13 respectively; then the rod 10 is withdrawn from the end loop 9; the bolts 7 and 8 are taken from the ends 35 of the slats 3 and 4, and said slats are swung on their pivots 5 and 6 into parallel engagement with the outer longitudinal slats 2^a and 2^b into the position shown in Fig. 3; the forward end of the device is then lapped 40 backwardly over the slatted end thereof as also shown in Fig. 3, and the device is then ready to be rolled up into a compact roll as 45 illustrated in Fig. 4, the rod 10, of course, being inclosed in the roll. The roll thus formed is then tied at each end with suitable cords 15; or the straps 12 may be removed from the eyes 11 and used for that 50 purpose if desired. The device can then be laid in the automobile or secured to the running board where it will take up very little room till it is again needed for use.

Of course, the transverse slats 3 and 4 may 55 be dispensed with if desired, and the device will still render efficient service, since in that case the ends of the longitudinal slats would still be well supported anyhow on the backs of the front and rear seats of the automobile, and would be held transversely taut thereon by means of the straps at the corners of the device.

Should it at any time be more desirable 60 to reinforce the outer ones 2^a and 2^b of the series of longitudinal slats 2 than to have the transverse slats at their ends, said transverse slats 3 and 4 may be swung on their pivots 5 and 6 into parallel flat engagement with said slats 2^a and 2^b respectively into 65 the position they are ordinarily brought to

occupy when the device is ready to be rolled up, and since the transverse slats are of the same length as the longitudinal slats, the opening for the bolt 7 in the transverse slat 3 will be brought into registration with the 70 opening for the bolt 8 in the slat 2^a, while the opening for the bolt 8 in the transverse slat 4 will be in registration with the opening for the bolt 7 in the slat 2^b. Then by simply passing the bolts 7 and 8 through 75 these registering openings, the slats 3 and 4 are securely fastened in parallelism with the slats 2^a and 2^b thereby doubling the strength of these two outside slats.

In Figs. 7 to 10 I have illustrated a modified form of connection between the free ends of the transverse slats 3 and 4 and the free ends of the parallel slats 2^a and 2^b. This modification dispenses with the need of the bolts 7 and 8, and is adapted to instantaneously engage the ends of the coöperating slats just referred to, and to automatically lock said ends together when they are brought into engagement with each other. This modification consists of two parts, one of 80 which is a metallic plate 16 struck up at one side to form the right-angled section 17, and at an adjacent side struck up to form an angular section composed of the vertical portion 18 terminating at its top in the inwardly bent horizontal portion 19. Each plate 16 is provided with suitable openings 85 20 for securing the plates to the free ends of the slats 2^a and 2^b, with the upturned sections 17 of the plates at the ends of the slats, 90 and the sections 18 at the outer sides thereof. 95

The section 18 is of the same height as the section 17, so that at its outer end the horizontal section 19 overlaps and rests on the top edge of the section 17. 105

Coöperating with each of the plates 16 is a spring 21 having openings 22 at its rear end for securing the spring in operative position relative to the plate 16, as clearly shown in Figs. 7 and 9. From these figures 110 it will be seen that the forward end of the spring is bent to rise upwardly above the plane occupied by the rear end thereof where it is secured to the slat 2^a. At its forward 115 free end the spring terminates in the downwardly bent section 23 which takes into an opening 24 in the slat 2^a just at the rear of the plate 16 to permit the upwardly inclined forward end of the spring to be depressed. 120

Referring further to Fig. 7, it will be seen that when the free end of the transverse slat 4 is swung toward the free end of the parallel slat 2^a, the end of the slat 4 will ride up on the spring 21, and that downward pressure applied to the slat 4 will depress the spring 21 and permit the end of the slat 4 to pass underneath the section 19 of the plate till said slat abuts against the vertical end section 17 of the plate, at which time the 130

forward end of the spring 21 is released and flies up at the rear side of the slat 4 to lock said slat in the position it has just assumed.

5 The downwardly extending end-section 23 of the spring could be dispensed with, in which case there would be no need of the opening 24 which receives it when the spring is depressed; but it will be seen that this end 10 23 of the spring acts as a bolt projecting into the opening 24, so that unless the spring were depressed, the end of the slat 4 would have to shear this bolt before the slat could be withdrawn from its locked position.

15 When it is desired to bring the transverse slats 3 and 4 into parallelism with the slats 2^a and 2^b, to which they are respectively pivoted at one end, (as for instance when it is desired to fold up the bed bottom), the 20 modification I have shown meets the requirements admirably, since the free ends of the end slats 3 and 4 are received under the horizontal sections 19 of the corner plates 16; and in order that these slats may 25 be the more easily entered underneath said sections 19, the tops of the free ends of the springs 21 are transversely inclined inward to provide an inclined surface on top of the springs for said end slats to ride up over. 30 This arrangement also causes the upper outer side of the free end of the spring to present a sharp corner to the under side of the slat which depresses the spring. This sharp corner extends in the direction of the 35 grain of the slat, so that it easily engages the slat and holds it against movement away from the plate 16.

Fig. 8 of the drawings shows the slat 3 riding up over the spring 21, almost ready 40 to be depressed and passed under the section 19 of the corner plate.

Having thus described the principles embodied in my invention, and having shown and described means for making a practical 45 application of the same, what I claim as new and desire to secure by Letters Patent is:—

1. A device of the character described, comprising a main portion formed of flexible material, said portion being provided 50 at one end with reinforcing bars secured thereto and extending a distance approximately equal to the distance from the back of one seat of an automobile to the back of the other seat, to adapt said reinforced portion of the device to rest at one end on the back of one seat and at the other end on the back of the other seat, the other portion of the device being without reinforcement; and 55 the device being provided at its ends with means for engaging an automobile.

2. A device of the character described, comprising a main portion formed of flexible material, said portion being provided at 60 one end with a series of reinforcing bars

secured thereto and extending longitudinally and transversely thereof, said reinforced portion extending a distance approximately equal to the distance from the back of one seat of an automobile to the back 70 of the other seat, to adapt said reinforced portion to rest at one end on the back of one seat and at the other end on the back of the other seat, said reinforcing bars being provided with means to cause all of said 75 bars to extend in a single direction when desired; and the device being provided at its ends with means for engaging an automobile.

3. A device of the character described, comprising a main portion formed of flexible material, one end of said portion being without longitudinal reinforcement and the other end being provided with a series of reinforcing bars secured thereto and extending in a longitudinal direction from the end of the device to the middle portion thereof; and a transverse bar at each end of the series of longitudinal bars, said transverse bars being pivoted at diagonally opposite corners of said reinforced portion of the device and adapted to swing on said pivots into parallelism with the longitudinal bars to cause said bars to all extend in a longitudinal direction when it is desired 90 to fold the device; the free ends of the transverse bars being provided with means for removably securing the same in their operative positions; and means at the four corners of said main portion of the device for 100 securing the same to an automobile.

4. A device of the character described, comprising a main portion formed of flexible material, one end of said portion being provided with a series of reinforcing bars 105 secured thereto and extending in a longitudinal direction from the end of the device to the middle portion thereof and a transverse bar at each end of the longitudinal bars, the other end of said main portion of the device being without longitudinal reinforcement, one end of each of said 110 transverse bars being removably secured to a corner of said reinforced portion of the device, said bars being adapted to swing on their pivots into parallelism with the longitudinal bars when it is desired to fold up the device; abutments on the longitudinal bars for engaging the transverse bars when they are swung into position at right angles to 115 said longitudinal bars; and means at the corners of the main portion of the device for securing the same in operative position on an automobile.

5. In a device of the character described, a reinforcing frame formed of a plurality of bars all approximately the same length, and comprising a series of longitudinally extending parallel bars and a transverse bar at each end of the parallel bars, said 120 125 130

transverse bars being pivoted to the ends of the outer ones of the parallel bars at points diagonally opposite each other, and adapted to swing on said pivots into parallelism with the longitudinal bars to cause all the bars of the frame to extend in the same direction when desired, the free ends of each of said transverse bars and the free ends of each of the outer ones of the longitudinal bars being provided with means for engagement with each other when the former are swung into contact with the latter; and means for automatically locking the ends of the former against movement 15 away from the ends of the latter when thus swung into engagement with each other.

6. In a device of the character described, a series of longitudinally extending parallel bars, and a transverse bar at each end 20 of the parallel bars, said transverse bars being pivoted to the outer ones of the parallel bars at points diagonally opposite each other, and adapted to swing on said pivots into parallelism with the longitudinal bars 25 to cause all the bars to extend in the same direction when desired, the free ends of the parallel bars being provided with means for receiving and automatically locking in engagement therewith the ends of the transverse bars when the latter are swung into engagement with the former.

7. In a device of the character described, a series of longitudinally extending parallel bars, and a transverse bar at each end of 35 the parallel bars, said transverse bars being pivoted to the outer ones of the series of parallel bars at points diagonally opposite each other, and adapted to swing on said pivots into parallelism with the longitudinal bars 40 to cause all the bars to extend in the same direction when desired; plates on the free ends of the outer ones of the parallel bars provided with means for receiving and holding the free ends of the transverse bars 45 when swung into engagement therewith; and springs coöperating with said plates to automatically lock the transverse bars in engagement with the longitudinal bars when the free ends of the two are swung together.

50 8. In a device of the character described, a series of longitudinally extending parallel

bars, and a transverse bar at each end of the parallel bars, said transverse bars being pivoted to the outer ones of the series of parallel bars at points diagonally opposite each other, and adapted to swing on said pivots into parallelism with the longitudinal bars to cause all the bars to extend in the same direction when desired; plates on the free ends of the outer ones of the series of parallel bars, each plate having an upwardly bent section at the end of the bar to which it is attached, and an upwardly-and-inwardly bent section at the outer side of said bar; and a longitudinally extending spring co-65 operating with each plate and secured on each bar at the side of the plate opposite the end of the bar, the inner end of said spring being secured to the bar and the outer end thereof being free and inclined upwardly. 70

9. In a device of the character described, a series of longitudinally extending parallel bars, and a transverse bar at each end of the series of parallel bars, said transverse bars being pivoted to the outer ones of the series 75 of parallel bars at points diagonally opposite each other, and adapted to swing on said pivots into parallelism with the longitudinal bars to cause all the bars to extend in the same direction when desired; plates on the 80 free ends of the outer ones of the series of parallel bars, each plate having an upwardly bent section at the end of the bar to which it is attached, and an upwardly-and-inwardly bent section at the outer side of said bar; and a longitudinally extending spring coöperating with each plate and secured on each bar at the side of the plate opposite the outer end of the bar, the inner end of the 85 spring being secured to the bar and the outer end thereof being free and inclined upwardly, said free upwardly-inclined end of each spring being also transversely inclined inwardly, to permit said transverse bars to ride up over said springs both longitudinally and laterally. 90

In testimony whereof I affix my signature in presence of two witnesses.

ALBERT G. MITCHUM.
